UNITED STATES PATENT OFFICE.

GEORGE H. WINANS, OF SALT LAKE CITY, UTAH.

HEAT-REGULATOR FOR CARS.

1,072,408.

Specification of Letters Patent.

Patented Sept. 2, 1913.

Application filed April 20, 1912. Serial No. 692,165.

To all whom it may concern:

Be it known that I, GEORGE H. WINANS, a citizen of the United States, residing at Salt Lake City, in the county of Salt Lake 5 and State of Utah, have invented a new and useful Improvement in Heat-Regulators for Cars, of which the following is a specification.

My invention relates to certain new and 10 useful improvements in heat regulating attachments for Pullman cars, sleeping cars, parlor cars and the like.

One object of my invention is to provide 15 a means for regulating the heat within the cars, without the necessity of shutting off the supply of heat.

Another object of my invention is to provide a means for covering the heating pipes to prevent the heat from entering the berth; 20 and allowing the heat from the heating pipes to enter the aisle of the car.

Another object of my invention is to provide a means for partly uncovering the heating pipes in the berth and thus allowing 25 the heat to escape and enter the berth.

Another object of my invention is to provide a means for preventing the heat from entering the aisle of the car and also preventing the heat from entering any part of 30 the car.

Another object of my invention is to provide a means for operating the pipe covering. The holes located in the pipe covering allow the heat to escape between the 35 seats when open or in line with each other.

Reference is had to the annexed drawings, forming a part of this specification, and to the figures of reference marked thereon, in which:—

40 Figure 1 is a side or end view of a berth in a Pullman car, with part of the seat cut away to illustrate my invention. Fig. 2 is a plan view of my invention, showing part of my invention in section, on line $x-x$.

45 Fig. 1. Fig. 3 is a sectional view of the flue through line $c-c$ Fig. 2. Fig. 4 is a plan view of the flue, showing it applied to the stationary pipe covering 1. Fig. 5 is a sectional view through line $b-b$ Fig. 1.

50 Fig. 6 is a front view of the holes 21 and 21' in the pipe covering. Fig. 7 is a cross sectional view through line $a-a$, Fig. 6.

Similar letters and numerals refer to similar parts throughout the several views.

55 A denotes the side of the car, B the seat within the Pullman car, C the pillow crate

under the seat, D the floor of the car, E the heating pipes along the side of the car, F the foot strip running along the side of the car and above the heating pipes.

60 1 is the stationary pipe covering, which is composed of three sections: the inner plate 2, the outer plate 3, and a sheet of asbestos 4 which is placed between the inner plate 2 and the outer plate 3.

65 5 is the sliding cover which is composed of three sections: the inner plate 6, the outer plate 7, and a sheet of asbestos 8 which is placed between the inner plate 6 and the outer plate 7. By this construction the heat

70 is prevented from entering the car when the holes 21 and 21' are closed, the sliding cover 5 being held in its relative position by cleats, forming runways 9, which are secured to the outer plate 3 of the stationary

75 cover 1. The holes 21 and 21' in said covers are for the purpose of allowing the heat to escape into the car when they are in line with each other. The plate 2 and the plate 7 have their edges flanged at 22 and 23 for

80 the purpose of securing the asbestos so that none of it will shake out onto the floor. The flanges 23 also answer as sliders which slide in the runways 9. The surfaces of said flanges are curved with the same degree of curvature as are the surfaces of said runways. This construction forms an easy sliding surface and at the same time holds the sliding cover closely against the stationary

85 cover.

90 Secured to the stationary cover is a box or flue 12, for the purpose of conducting the heat from the pipes E into the center of the car; said flue being constructed with an inner box 14 and having a sheet of asbestos 95 13 placed between the outer box 12 and the inner box 14, thus preventing the heat from escaping through the sides of the box. In the end of the box 12 is placed a door 15, which is held closed by a spring 16 when 100 it is desired to keep the heat within the box.

105 Located on the outer plate 3 of the stationary cover are rollers 17, over which passes a cord 18; said cord has a handle 20 at one end and the other end is secured to the sliding cover at 19. The cord 18 is for the purpose of operating the sliding cover.

110 In applying my invention to a car, I first place the inner edge of the stationary cover 1 under the flange 11 of the foot plate F and secure the right-angular projection 10 to the floor. I then place the box 12 under

the seat and secure it to the stationary cover as well as to the floor. This manner of securing them holds the box and cover firmly in their relative positions. When I wish to prevent the heat from entering the car I pull on the handle 20; this closes the holes 21 in the pipe cover by pulling the sliding plate over to one side as shown in Figs. 1 and 2. I then close the door 15 in the end 10 of the box 12, thus keeping all of the heat within the chamber 25 around the pipes F. When I wish to have the heat in the center of the car I open the door 15 in the box 12; this allows the heating of just the aisle, at 15 night when the curtains of the berths are drawn. In the event that I wish heat in the berth and not in the center of the car I close the door 15 and pull on the cord 20'; this pulls the sliding cover over to the opposite side and places the holes 21 and 21' in a line with each other thus allowing all of the heat to enter the berth. If I wish the heat in the center of the car, as well as in the berth, I open the door 15, which allows heat to escape into the aisle. Since heat is also escaping through the pipe covers, and the door 15 is now open, the heat is escaping through both openings and heating the berth and the aisle at the same time.

30 When my invention is applied to the halls of a car, or where there are no seats, I substitute a knob in the hole 19 in place of the

cord 18, which is only used when there is a distance between the operator and the pipe covers.

Having thus described my invention, what I claim as new and desire to secure by Letters Patent is:—

A casing for inclosing heating pipes comprising inner and outer rigid walls and an intermediate wall composed of a material of low conductivity, said casing having an opening extending through said walls, the margin of one rigid wall being bent about said intermediate wall into engagement with the remaining rigid wall throughout the margin of said opening to inclose the intermediate wall, and a cover plate slidably mounted on said casing and comprising inner and outer rigid walls and a wall intervening said inner and outer rigid walls and composed of a material of low conductivity, said cover plate having an opening extending through the walls thereof and adapted to be brought into and out of register with the opening in said casing, the margin of the opening of one of the rigid walls of said cover plate being bent about said intervening wall and into engagement with the remaining cover wall, substantially as described.

GEORGE H. WINANS.
